UNITED STATES PATENT OFFICE.

REUBEN STANLEY SMITH AND THORVALD HANSEN, OF MILWAUKEE, WISCONSIN,
ASSIGNORS TO A. O. SMITH CORPORATION, OF MILWAUKEE, WISCONSIN, A
CORPORATION OF NEW YORK.

LAPPING PRESS.

1,417,581.

Specification of Letters Patent. Patented May 30, 1922.

Application filed July 26, 1920. Serial No. 399,215.

To all whom it may concern:

Be it known that we, REUBEN STANLEY SMITH and THORVALD HANSEN, citizens of the United States, and residents of the city 5 of Milwaukee, in the county of Milwaukee and State of Wisconsin, have jointly invented certain new and useful Improvements in Lapping Presses, (Case #115); and we do declare the following to be a full, 10 clear, and exact description thereof, such as will enable persons skilled in the art to which the invention pertains to make and use the same, reference being had to the accompanying drawings for an illustration of 15 one form of construction in which our invention has been embodied.

The invention relates to lapping presses.

The object of our invention is to provide a mechanism which will expeditiously turn, 20 bend or fold and flatten the projecting ends of the flanges of a channeled cross bar, so as to form fastening ears by means of which the cross bars may be connected to the side bars of an automobile or other vehicle frame, 25 to constitute a rigid, unitary and permanent structure. The ears formed by bending the projecting ends may extend into the channel of the cross bar, or such ears may be made to radiate from the bar. In some types of 30 bars the said ears may be tandem to each other. But the direction in which the ears are made to extend will be merely an incident in the production of the frame, and dependent upon the construction of the frame as a 35 whole. Usually, such fastening ears will stand at an angle of 90° with relation to the longitudinal or axial line of the cross bar upon which they are formed, but such angle may be varied to meet the requirements of 40 any particular type of frame.

In an application filed January 21, 1918, Serial #212,984, by R. Stanley Smith, patented November 15, 1921, #1,397,020, one of the parties hereto, there is disclosed an 45 assemblage of machines, such assemblage including machines which by their related, connected and successive operations, punch from metal plates and strips the side and cross

bar and other blanks used in constructing an automobile or other vehicle frame, draw such 50 blanks into shape according to the requirements appertaining to each particular type of frame which it is desired to produce, perform the necessary milling operations upon the shaped blanks, assemble the several 55 constituent parts of the frame in their relative positions, and permanently secure all of such parts in their respective positions, so that in a continuous operation of mechanical devices a completed automobile or other vehicle 60 frame is automatically produced. The present invention is designed to form an element of the assemblage of machines referred to. But it will be understood that the present structure has capacity for use in the performance of its functions independently of 65 such assemblage.

For the purpose of presenting the flanged cross bars in position for operation thereon by the lapping mechanism embodied in the 70 present invention, we may use a turret such as is disclosed in the patent above mentioned. In its periodic movements, the turret presents the flanged cross bars to the lapping mechanism, by the operation of which the 75 ends are bent or lapped to form the fastening ears, this operation taking place during the periods of rest to which the said turret is subjected in its predetermined cycle of movement.

When a cross bar is presented to the lapping mechanism by the turret referred to, or otherwise, such bar is firmly held by clamping members which co-act with the lapping dies, so that the projecting end portions may 85 be bent to form the fastening ears at the exact points desired in the length of the cross bar.

The invention involves a novel form of lapping die which is so mounted as to have 90 a movement of partial rotation about an axis which is co-incident with that on which the projecting end portion of the cross bar is turned. The lapping dies are constructed so as to have capacity for varying the arc in 95 which they oscillate, to permit reverse move-

ment, and bend the projecting end portions either toward or from the longitudinal axis of the cross bar.

Novel means have been provided for actuating the lapping dies.

The novel features of my invention will be pointed out in the appended claims.

In the drawings which accompany this specification:

10 Figure 1 is a side view in elevation on the central line 1—1, Fig. 2, and partly broken out to show the arrangement of the elements constituting our improved lapping mechanism.

15 Fig. 2 is a plan view, but partly in section on the line 2—2, Fig. 1, of the lapping mechanism showing Fig. 1.

20 Fig. 3 is a diagrammatic view showing the operation of the lapping dies when acting to fold the projecting ends of the flanges of the cross bar into the channel thereof.

25 Fig. 4 is a similar view showing the operation of the lapping dies when folding such projecting ends outwardly, so that the latter will extend in opposite directions, and away from the cross bar.

30 Fig. 5 is a fragmentary view in elevation, looking from the left in Fig. 1, and showing the arrangement of the lapping mechanism at one end of the cross bar.

Fig. 6 is a similar view looking toward Fig. 1, and toward the right, Fig. 5.

In the drawings which accompany this specification, 10 indicates the base upon which the lapping mechanism constituting our invention is mounted. Separate housings 11 and 12, each containing a lapping mechanism for operating upon the projecting portions at each end of the cross bar, are mounted upon the said base, and have capacity for movement toward and from each other, so that their relative positions may be adjusted to meet the changed conditions involved in the production of cross bars of 45 different lengths. It will be understood that the two lapping mechanisms operate simultaneously upon the two ends of the cross bar, so that the longitudinal stresses exerted in the operation of one lapping mechanism 50 upon one end of the cross bar, are neutralized by like stresses exerted at the same time upon the other end of the cross bar by the other lapping mechanism.

To permit the relative adjustment of the 55 two lapping mechanisms, we provide the base 10 with guides 13 and 14, upon which the housings 11 and 12, with their contained operating elements, are free to be moved toward and from each other. Parallel racks 60 15 and 16 are set in the base 10, and these racks are in mesh with pinions 17 and 18, fixed upon a shaft 19 which is journaled in the housing. By means of a hand wheel 20, upon the outer end of the shaft 19, the pinions 65 may be rotated to cause the housings to

change their relative positions, and thus the desired precise adjustment of the housings may be secured. A set screw 21, threaded into a lug 22 on the base of each housing, and bearing against the base 10, serves to 70 clamp the housing with its lapping mechanism in the position to which it has been adjusted, and hold the same against accidental displacement.

A shaft 23 extends through and is journaled for oscillation in both housings. This shaft 23, is splined throughout its length, so that the two housings may be relatively adjusted in the manner hereinbefore described, without disturbing the longitudinal arrangement of the said shaft. A radial arm 24 is keyed upon the shaft in the space between the two housings, and a connecting rod 25 extends from the forked free end of the radial arm 24, to any suitable actuating mechanism, arranged as convenience may indicate to be desirable. By means of such actuating mechanism the shaft 23 may be given oscillatory movements, for a purpose to be later described.

90 Each of the two lapping mechanisms constituting a set, is ordinarily provided with two lapping dies, which in the construction illustrated, are intended to act upon the projecting portions of the two vertically standing flanges with which each cross bar is formed. The two lapping dies of the mechanisms of each set are similar in construction and operation, but have a slightly different arrangement, imposed by the limitations of space wherein which they are required to perform their work, and the necessity for adjustment of the operating zone of one of the dies when cross bars of different widths are produced. It will be sufficient for the purposes of the present disclosure to describe somewhat specifically the more complexly constructed one of such dies, together with the manner of its mounting, it being understood that the construction of the other is in all essentials the same, and differs only in its relative location, and the lack of the provisions for the zone adjustment before referred to.

110 Vertical shafts 26 and 27, disposed in parallel planes and separated on centers by the width of the cross bar, viewing Fig. 1, support the lapping dies at their contiguous or adjacent ends. These shafts have a movement of partial rotation or oscillation 115 through an arc of 90°, to actuate the lapping dies to cause the latter to perform their function of turning the projecting ends of the cross bar, to form fastening ears or laps. The said shafts 26 and 27 have also 120 an axial or longitudinal movement, through which the lapping dies supported thereon, may be properly positioned to turn the projecting ends of the cross bar, and then retracted or withdrawn so as to allow a clear- 125 130

ance space for the free movement of the cross bar into and out of position for the operation of the lapping mechanisms. The shaft 26 is guided at its upper end in a 5 forked bracket 28, which latter is adjustably mounted at the top of the housing, and held in a set position by means of bolts passing through slots in the bracket. A radial arm 29 is splined upon the shaft 26, and is received in the fork of the bracket, so that the said shaft may have longitudinal movement without disturbing the relative position of the said radial arm.

The lower end of the shaft 26 is journaled in an adjustable bearing 30 connected to a slide 31, guided upon the front of the housing, and partaking of the longitudinal movement of the shaft 26. A collar 32, set on the shaft 26, above the bearing 30, restrains the downward movement of the shaft 26, independently of that of the slide 31. The journal 30 is constructed so as to have a dove-tail engagement with the bottom plate 33 of the slide 31, in the manner 25 shown in Fig. 5, so that the shaft and slide will move together vertically. An adjusting screw 34 threaded into the journal 30, and restrained from longitudinal movement by a lug on the slide 31, provides a compensatory adjustment, whereby the parallel 30 alignment of the shaft 26 with relation to the shaft 27, may be changed so as to provide for the treatment of cross bars of different widths.

35 The corresponding adjustment of the bracket 28, by means of the provisions hereinbefore described, enables the shaft 26, to be maintained in parallelism. The bottom plate 33 of the slide 31, is slotted as at 36, 40 to permit the lateral movement of the shaft 26, when the adjustment described is being made. Set screws 37, clamp the journal 30 to the slide 31, after adjustment.

At its lower end, the shaft 26 is provided 45 with a flanged head 35, to which the lapping die 38, pertaining to the shaft 26, is attached by any suitable fastening means. The said head is grooved diametrically upon its face for the reception of a correspondingly 50 formed rib on the base of the die. By this means the registry of the die and the head is secured, and the two parts are thus interlocked so as to rotate together.

Figs. 3 and 4 show the configuration of 55 the angular lapping dies, which are provided with vertical faces standing 90° apart. The axis of rotation of the die is approximately co-incident with the line upon which the projecting end of the cross bar is turned or 60 bent to form the fastening ear. The base of the die may be concentric with the shaft head 35, and the wings leading from the base of the die to the extremity thereof may be tapered, as indicated at 39.

65 The shaft 27 is guided in a fixed bear-

ing 270, extending from the front of the housing, and is journaled at its upper end in the lower slide 31, and does not need the provisions for lateral adjustment described in connection with the shaft 26, although as 70 stated, both shafts are equipped with dies of like formation. The longitudinal movement of the shafts 26 and 27 to bring the dies supported thereon into position to perform the lapping operations, is effected by 75 means of centrally pivoted floating levers 40 and 41, connected at one end to the slides 31, so as to reciprocate the same, and at their other ends by means of links 42 and 43, to a two arm lever 44, splined upon the shaft 80 23, before referred to, and partaking of the partial rotatory or rocking movements of the latter.

The upper slide 31 supports slidably mounted clamping members 46, formed as 85 wedges, which co-act with other clamping members 47, carried by the lower slide 31, such other clamping members being likewise formed as wedges. The wedges 46 are supported and guided in an undercut slot 460, 90 forming in an extension 350 of the upper slide 31. The lower slide 31 carries also a filler block 48, designed to enter the channel of the cross bar at the end thereof, and bear against the side flanges of such cross bar, 95 as the slides approach each other. In the same movement, the inclined surfaces of the wedges 46 and 47, upon the respective slides, co-act so as to cause the movable parts 46 to bear against the sides of the flanges and 100 tightly clamp the cross bar upon the filler block 48. The acting faces of the lapping dies 38, stand parallel to the radius of the shaft upon which they are supported, and offset from such radius a distance equal to 105 the gauge of the stock of the cross bar, so that the folding line of the projecting end of the cross bar will be co-incident with the axis of the shaft carrying the lapping die.

110 A quarter turn of the shafts 26 and 27, by means of mechanisms to be described, will cause the dies 38 to bend or flatten the projecting ends of the cross bar against the filler block 48, in case such projecting ends 115 are to be turned in directions toward each other and to extend into the channel of the bar. The clamping members 46 and 47 are adjustable, and the filler block 48 is interchangeable, so that cross bars of different 120 widths may be properly treated by suitable adjustments and replacements of the said parts. When the projecting ends of the cross bar are to be turned or bent radially from the axis of the bar, or to stand in tandem relation, other lapping dies equipped with properly positioned acting faces will be supplied to the heads of the shafts 26 and 27. In the construction illustrated, the shafts 125 26 and 27, are given a movement of partial 130

rotation through an arc of about 90°. Such rotary movement is effected by means of the radial arm 29, before referred to, splined upon the shaft 26, and a like arm similarly arranged with relation to the shaft 27. These radial arms are connected at their free ends to links 50 and 51, respectively, the other ends of which are attached to cranks 52 and 53, formed upon the extreme ends of aligned shafts 54 and 55, connected and driven by a set of bevel gears 56, the intermediate one of which is provided with a sleeve 59, splined upon a line shaft 57, journaled in the movable housings 11 and 12. The link 50, hereinbefore referred to as connecting the radial arm 28 of the shaft 26, and the crank 52 on the shaft 54, is provided with a turn buckle 58, to provide a means for conforming the length of the said link, in the lateral adjustment of the shaft 26. The boss on the lower arm of the crank 53, on the shaft 55, serves as a thrust bearing, to preserve the vertical position of the said shaft.

In Fig. 2, we have shown a portion of the intermittently revolving turret 60, which may constitute an element of the assemblage disclosed in the patent hereinbefore referred to, and which is provided at its periphery 30 with bars or clamps 61, into which the cross bars 62 are set, and by which they are positioned and properly presented to the lapping mechanism, in the intermittently movements of the turret, so that the projecting ends 63 on the cross bar may be bent or turned so as to form the fastening ears or laps 64, in the operation of the lapping dies.

Each of the housings is cut away in the rear of the lapping mechanisms, as indicated 40 at 66, in Figs. 1 and 6, so as to provide a clearance for the passage of the cross bar 62, when presented by the turret. The shafts 26 and 27, carrying the lapping dies operating at each end of a cross bar, will be 45 made to rotate in the desired directions by any suitable arrangement of the radial arms with respect to the shafts 26 and 27, upon which the said radial arms are splined.

While in the foregoing we have described 50 the vertical shaft 26 as adjustable in a parallel plane with reference to the shaft 27, it will be understood that the said shaft 26 is susceptible of adjustment in a plane which may be slightly inclined to the plane of the shaft 27. This adjustment of shaft 26 may be resorted to in cases where it is desired 55 to vary in a slight degree the arrangement of the fastening gears produced upon the ends of the channel cross bars. The angularity of the shaft 26 with relation to the shaft 27 will depend upon the degree of 60 separate adjustment of the bracket 28 and the slide 31.

The arrangement of each set of lapping 65 die shafts 26 and 27 so as to extend in op-

posite directions from the field in which they work, enables the lapping dies of each set to be brought into close relation with each other, and permits them to operate upon cross bars of narrow cross sectional 70 constructions. The construction and arrangement are such that the shafts 26 and 27 may be laterally adjusted until their axes approach a line which is substantially coincident thereto.

In the claims we refer to the lapping dies and shafts as rotating or being rotatable, and as actuated, these terms having been used merely as convenient definitions of the reciprocatory rotations or oscillations to 80 which the said parts are subjected in the operation of the machine.

In using the lapping mechanism involved in the present invention, the flanged cross bar may be manually placed in position for 85 the operation of the lapping dies, in case it is not expedient to use automatic devices, such as the turret referred to, for thus positioning the cross bars.

Modifications of the structure and in the 90 arrangement of the parts, may be made without departing from the spirit of our invention. Such changes as may be made will be within the scope of our invention.

Having thus described our invention, 95 what we claim and desire to secure by Letters Patent of the United States, is:

1. A lapping press for bending the projecting ends of the flanges of a channelled bar, including means for supporting the bar, clamping jaws movable toward and from each other to engage the side flanges of a channel bar carried by said support, a pair of rotatable shafts each having a lapping die adapted to bear against the projecting end of one of the flanges, the axis of each shaft being in substantial alignment with the bending line of the said projecting end, and means for simultaneously actuating said shafts to turn the projecting 110 ends of said flanges from their initial planes.

2. A lapping press for bending the projecting ends of a flanged bar, including a plurality of shafts supported in positions longitudinally and laterally separated from each other, co-acting clamps adapted to engage and hold the flanged bar between them, lapping dies mounted on the shafts and adapted to bear against and turn the projecting ends of the flanged bar, and means 120 for rotating the shafts.

3. A lapping press for bending the projecting ends of the flanges of a channelled bar, comprising a separable clamp for holding the bar, a lapping die movable with each member of the separable clamp, means for separating the clamping members and dies to allow movement of the bar between them, and means for actuating the lapping dies to turn the said projecting ends into angular 130

positions with respect to the axis of the channeled bar.

4. A lapping press for bending the projecting parallel ends of the flanges of a channeled cross bar, comprising a separable clamp for holding the cross bar, means for separating the clamping members to permit movement of the work, a lapping die movable with each member of the clamp, and 10 rotatable upon an axis parallel to the plane of such separating movement, means to impart clamping movement to the said members, and means to rotate the lapping dies to turn the said projecting ends into angular 15 positions with respect to the flanges of which they form a part.

5. A lapping press for bending the projecting parallel ends of the flanges of a cross bar, comprising means for clamping the said 20 bar at the bending line, rotating shafts carrying lapping dies for operation upon the said projecting ends, and means for actuating the said shafts to turn the said ends into angular positions with respect to the 25 flanges of the bar.

6. A lapping press for bending the projecting parallel ends of the flanges of a cross bar, comprising means for clamping the said 30 bar at the bending line, axially parallel rotating shafts carrying lapping dies for operation upon the said projecting ends, and means for actuating the said shafts to turn the said ends into angular positions with respect to the flanges of the bar.

35 7. A lapping press for bending the projecting ends of the flanges of a channeled cross bar, comprising lapping dies arranged for simultaneous operation upon the said projecting ends to turn them from the planes 40 of the flanges, in combination with means for so actuating the dies, whereby the stresses generated in the bending operations are neutralized by the longitudinal resistance of the cross bar.

45 8. A lapping press for bending the projecting ends of a bar, comprising means for presenting bars in intermitting succession with the ends of each bar in position for operation thereon, clamping means for the 50 bar, lapping dies adjacent each end of the bar, and means for actuating the lapping dies to turn the ends of the bar during the periods of rest of the presenting means.

55 9. In a lapping press for bending the projecting ends of a bar, lapping dies movable toward and from each other to permit movement of the work into position between the said dies for a lapping operation, means for so moving the lapping dies, and other means 60 for actuating the said dies to change the line of the bar.

65 10. In a lapping press, a pair of lapping dies oppositely movable in separated parallel paths into and out of the field of their operation to permit movement of the work

into bending position in the said field, means for so moving the lapping dies, and means for simultaneously actuating the said lapping dies to change the lines of the work by bending pressure exerted by the said dies. 70

11. In a lapping press, a pair of lapping dies, means for actuating the said dies to perform bending operations, and means for effecting a relatively lateral adjustment of the said dies into position for operation upon 75 work of different widths.

12. In a lapping press for bending the projecting ends of metal bars, a base, housings thereon, each housing containing a lapping mechanism for operating upon the ends 80 of the bar, and means for adjusting the said housings with relation to each other, whereby the lapping mechanisms contained therein may be positioned to bend the ends of bars of different lengths. 85

13. In a lapping press for bending the projecting ends of metal bars, a base, housings thereon, each housing containing a lapping mechanism for operating upon the ends of the bar, means for adjusting the said 90 housings with relation to each other, whereby the lapping mechanisms contained therein may be positioned to bend the ends of bars of different lengths, and common power connections for jointly actuating the said lapping mechanisms. 95

14. A press provided with means for holding a cross bar, lapping dies arranged at each end of the holding means and co-operating therewith to turn the projecting ends 100 of the cross bar and form fastening ears, and means for actuating the lapping dies.

15. A lapping press for simultaneously bending the projecting ends of the flanges of a channeled cross bar, comprising lapping 105 dies arranged for operation at both ends of the cross bar to turn said ends from the planes of the flanges, and means for so actuating the dies.

16. A lapping press for bending metal 110 parts, comprising work clamping means, a rotatable shaft having its axis substantially in line with the axis about which the work is to be bent, said clamping means being adapted to engage the work in close proximity to the bending line, a die carried by said shaft, means for actuating the said shaft, and adjustable bearings for the shaft, whereby the axes of the latter may be inclined, and lapping operations performed 115 at various angles with reference to the portion of the work engaged by the clamping means.

17. A lapping press for bending the longitudinally projecting ends of the flanges of 120 channel bars, including the combination with bar supporting means, of two sets of movable clamping jaws, means for actuating said sets of clamping jaws in opposite directions to engage between them the flanges 125 130

of a channel bar carried by said support, a set of shafts each having a die adapted to bear upon the projecting portion of one of the side flanges, with one face of the die and 5 the axis of the shaft substantially alined and co-incident with the line about which the flange is folded, and means for simultaneously oscillating said shafts in opposite directions, whereby the projecting portions of 10 said flanges may be turned by said dies from the plane of the bar.

18. A lapping press, including a plurality of shafts, bearings supporting the shafts in positions lineally and laterally offset, 15 set from each of the other and with ends contiguous, co-acting clamps supported from the respective bearings, and adapted to engage the work between them, lapping dies mounted on the contiguous ends of the shafts 20 and adapted to bear against projecting portions of the work, and means for actuating the shafts.

19. A lapping press, including the combination with a set of co-acting clamping 25 jaws, means for supporting and actuating said jaws toward and away from each other, and an oscillatory member associated with one of the jaws and adapted to turn about an axis in the plane of the gripping face of 30 the associated jaw, whereby said jaws may be adjusted to clamp a blank between them and said oscillatory member subsequently actuated to fold the blank about said axis.

20. In a lapping press, the combination 35 with a work gripping jaw, of an oscillatory member adapted to swing upon an axis parallel and adjacent to one margin of the gripping jaw and having an acting face adapted to bear upon the work upon one side of said 40 gripping jaw in a plane which includes the axis of oscillation of said member.

21. In a lapping press, the combination 45 of a set of clamping members adapted to engage the work between them, an oscillatory member associated with one of the clamping members and having an acting face adapted to engage the work at one side of the associated clamping member, and means for actuating the oscillatory member 50 to effect a folding operation while the clamping members are in clamping position.

22. A lapping press, including the combination 55 with a jaw supporting member, a set of jaws having oppositely disposed gripping faces, wedge actuating abutments connected with said jaws and having inclined faces, a wedge supporting member adapted for relative movement toward and away from said jaws along lines parallel with their gripping faces, wedge jaws movably mounted 60 on said wedge supporting member and adapted to move upon the inclined faces of the wedge abutments, and along the wedge supporting member into gripping relation 65 to the first mentioned jaws, folding dies as-

sociated with the respective jaws of one of the sets, and means for actuating said dies when the jaws are in gripping relation to each other.

23. A lapping press, including the combination 70 with sets of co-acting clamping devices, of a set of oscillatory shafts, each provided with a die having an active face substantially in line with the axis of the shaft and adjacent to the side margin of one of the jaws, and means for actuating the shafts to effect a folding operation upon the work when the jaws are in clamping relation to each other.

24. A lapping press for channel bars, including 80 the combination with sets of co-acting clamping devices adapted to engage the side flanges of the channel bar, of a set of oscillatory die supporting members, and dies thereon, each having an active face substantially in the axis of oscillation of the said supporting member, and adjacent to the side margin of one of the clamping jaws.

25. A lapping press for channel bars, including 90 the combination with sets of co-acting clamping devices adapted to engage the side flanges of the channel bar, of a set of oscillatory die supporting members, and dies thereon each having an active face substantially in the axis of oscillation of the 95 said supporting member, and adjacent to the side margin of one of the clamping jaws, the clamping jaws of each set being adapted to move upon each other along lines substantially parallel with said axis of oscillation, and being provided with means whereby one of the jaws is also subjected to a wedging action to force it transversely to said line in the direction of the other.

26. A lapping press, including separable 105 sets of clamping jaws, lapping dies, one associated with one of the jaws of each set, means for separating the jaws to allow the presentation of the work between them, and means for oscillating the said dies about an 110 axis parallel to the lines of jaw separation.

27. A lapping press, including separable 115 sets of clamping jaws, lapping dies, one associated with one of the jaws of each set, means for separating the jaws to allow the presentation of the work between them, means for oscillating the dies about an axis 120 parallel to the lines of jaw separation, and means for effecting a gripping engagement of the jaws upon the work at an angle to the lines of separating movement.

In testimony whereof, we have signed our names at Milwaukee, this 22nd day of July, 1920.

R. STANLEY SMITH.
THORV. HANSEN.
